UNITED STATES PATENT OFFICE.

LEMON M. SMITH, OF NEW YORK, N. Y.

BRUSH.

Application filed October 24, 1925. Serial No. 64,633.

This invention relates to brushes and has for its object the provision of a novel or improved brush of the scrubbing or cleaning type so constructed and arranged that the edges thereof may be used as well as the active face, it being consequently easier to clean out corners or edges of sinks, lavatories or in fact anything else to be cleaned and kept sanitary.

10 An important object of the invention is to provide a brush in which the bristle tufts stand at different angles so that they will have a better action on the surface rubbed over.

15 Another object is to provide a brush having at its edge a removable portion of twisted wire carrying bristles, this removable portion or member being embracingly engaged upon the brush head or back and 20 being removable when worn so as to be replaced by a new one as occasion may arise.

25 An additional object is to provide a device of this character which will be simple and inexpensive to manufacture, easy to use, positive in action, efficient and durable in service, and a general improvement in the art.

With the above and other objects and advantages in view, the invention consists in 30 the details of construction and arrangement of parts to be hereinafter more fully described and claimed, and illustrated in the accompanying drawing in which:

Figure 1 is an elevation of a brush embodying the invention,

Figure 2 is a cross section on the line 2—2 of Figure 1,

Figure 3 is a longitudinal section on the line 3—3 of Figure 1, and

40 Figure 4 is a detail view showing the removable rim or circumferential member.

Figure 5 is a rear view of the brush showing the wires interlocked.

45 Referring more particularly to the drawings I have shown the brush as comprising a head 10 of any suitable material, size and shape and provided, preferably, with a handle 11 which may be integral therewith. In the present instance the head is shown as of substantially elliptical shape and convex in cross section at both its back and face. The face portion is formed with a series of sockets 12 within which are mounted tufts of bristles 13. It will be observed that

these tufts follow the contour of the head 55 and that they are at different angles so that they will be properly presented to the surface to be cleaned when the brush is rubbed thereover.

A very important feature is the provision 60 of a frame member 14 here represented as formed of twisted wire though possibly capable of being made in some other manner. This frame member carries a plurality of bristle tufts 15 which extend outwardly 65 therefrom. The edge of the brush head is grooved as indicated at 16 for the reception of this member 14 and after it is placed in position it is secured by means of hooks 17 at the ends of the member 14, which hooks 70 are adapted to be interengaged.

Of course the brush is used in substantially the same manner as any other but it has the great advantage of being equipped with the brush structure at the rim which 75 will greatly facilitate the cleaning out of any dirt or other matter accumulated within the corners or edges of sinks or in fact anything else. Clearly, when the brush structure at the rim or outer edge of the 80 head becomes worn the hooks may be disengaged and the frame 14 removed and replaced by a new one without it being necessary to discard the brush itself.

While I have shown and described a preferred embodiment of the invention, it should be understood that I reserve the right to make such changes in the form, construction and arrangement of parts as will not depart from the spirit of the invention or 90 the scope of the subjoined claims.

Having thus described the invention, I claim:

1. A brush comprising a head having one face provided with bristle tufts, the head 95 being formed at its edge with a groove extending entirely therearound, and a band of twisted wire carrying bristle tufts seated within said groove.

2. A brush comprising a head having one 100 face provided with bristle tufts, the head being formed at its edge with a groove extending entirely therearound, and a twisted tuft carrying core seated within said groove, the ends of said core being formed with 105 hooks, said hooks being interengaged.

In testimony whereof I affix my signature.
LEMON M. SMITH.
